UNITED STATES PATENT OFFICE.

CHARLES H. MYERS, OF BUFFALO, NEW YORK.

CARBURETER FOR STATIONARY ENGINES AND OTHER PURPOSES.

1,070,514.

Specification of Letters Patent. Patented Aug. 19, 1913.

Application filed February 24, 1910, Serial No. 545,773. Renewed January 15, 1913. Serial No. 742,310.

To all whom it may concern:

Be it known that I, CHARLES H. MYERS, a citizen of the United States, residing at Buffalo, in the county of Erie and State of New York, have invented a new and useful Carbureter for Stationary Engines and other Purposes, of which the following is a specification.

This invention relates to means for vaporizing hydrocarbons for use in the explosive chamber of stationary combustion engines, and consists in certain novel features of construction and arrangement of parts which are illustrated in the accompanying drawings and will be hereinafter fully described and then pointed out in the claims.

In the accompanying drawings, Figure 1 is a central vertical longitudinal section of a carbureter embodying my invention. Fig. 2 is an end elevation of the same partly broken away. Fig. 3 is a view partly in horizontal section and partly in plan of my device. Fig. 4 is a transverse vertical section. Fig. 5 is a detail view of one of the partitions. Fig. 6 is a detail section of the throttle valve arranged in the outlet.

In carrying out my invention, I employ a housing or casing 1 which may be of any desired size and form and which is provided at one end with an air inlet 2 over which is placed a screen, as clearly shown in Figs. 1 and 2. Over this air inlet I secure a dome or semi-spherical hood 3 from which rises an air inlet pipe 4 provided at its upper end with a cup-shaped enlargement 5 provided with a transverse bar 6 at its open upper end in which is mounted a threaded shaft or screw 7 carrying a hand wheel 8. By turning this hand wheel, the screw 7 will be caused to move through the bar 6 and thereby bring the hand wheel closer to or farther from the open end of the cup 5 and thereby control the inlet of air to the carbureter. This adjustment is effected at the factory and is determined by the size of the carbureter and the capacity of the engine to which it is to be fitted, and the adjustment is not subsequently changed. In the upper side of the housing 1, at the end opposite the air inlet, I provide a screened outlet 9 through which the vapor-laden air may pass so as to escape through the pipe 10 to the engine. This pipe 10 leads from a dome 11 which is secured over the outlet opening 9 and the opposite end of the pipe 10 is secured to or formed integral with a

valve casing 12 in which is mounted a hand-operated valve 13 adapted to cut off the outlet entirely or to vary the amount of vapor permitted to escape by being moved more or less from its seat, as will be readily understood. The seat for this valve 13 is formed on one side of a dome or cup 14 within which I provide one or more screens 15 and from which a pipe 16 leads to the engine.

Within the housing 1, I provide a plurality of superposed compartments or containers 17 and in each of the said compartments or containers, I provide an absorbent oil holder 18 which is preferably lamp wicking cut into proper lengths and set on end within the compartments so that the capillary passages will be vertically disposed. The wicking is held in the compartments by a series of rods 19 disposed transversely therein below the upper edges of the same, whereby oil fed to the uppermost compartment will be permitted to overflow therefrom after saturating the absorbent material and pass into the next lower compartment, where the same action will occur, whereby the several compartments will be successively supplied with the oil.

In the form of the invention illustrated in the drawings, the several compartments are provided by a series of pans disposed longitudinally within the housing and arranged in staggered relation, as will be most readily understood on reference to Fig. 4. The lowermost compartment will fill the entire bottom of the housing, while the next superposed compartments will have their longitudinal edges in contact with each other and with the sides of the housing, thereby leaving spaces 20 between the sides of the housing and the compartments and between the compartments, as clearly shown in Fig. 4, so as to permit a large volume of air to pass over the lower compartment, as will be readily understood. The third horizontal row of compartments will be so disposed that the spaces between the same will be arranged over the subjacent compartments, as clearly shown in Fig. 4 and, consequently, air passing through the said openings will be compelled to travel over the lower compartment, and the saturated absorbent material therein. The oil is admitted to the uppermost compartments through a valve 21 connecting a feed cup 22 with the top of the housing and will pass from the said valve di-

rectly onto the absorbent material in the uppermost compartments. From these compartments, the oil will overflow through openings 23 in one end of the same into the 5 next subjacent compartments and will overflow from the said compartments through openings 24 at the opposite end thereof, and so on to the lowest compartments. In order to further provide for an even distribution 10 of the oil through the absorbent material and the several compartments, I employ a series of longitudinal partitions 25 which are provided with perforations 26 and extend from end to end of the several compartments, as clearly shown in Fig. 3. 15 These partitions extend above the absorbent material, as shown clearly in Figs. 1 and 4 and aid in supporting the superposed compartments. They also permit the surplus oil 20 to spread evenly through the absorbent material and to pass readily from one compartment to the next lower compartment. This spacing of the partitions, furthermore, serves to divide the air current passing over 25 the absorbent material and, consequently, bring the said air current into intimate contact with the entire surface of the absorbent material, so that the oil held by the said material will be thoroughly vaporized and 30 taken up by the air and a rich hydrocarbon gas supplied to the engine.

It will be understood, of course, that the device may be made of any desired capacity and is charged with the hydrocarbon oil at 35 such intervals as may be necessary by having the said hydrocarbon simply poured through the cup 22 and the valve 21 connected therewith. A stop cock 27 is provided at one end of the housing immediately 40 above the upper surface of the absorbent material in the lowest compartment, and this stop cock is opened when the device is to be charged. The hydrocarbon flowing into and from the several compartments will 45 eventually reach the lowest compartment and will saturate the absorbent material therein and will then tend to collect on the upper surface of the same. This excessive oil will escape through the stop cock 27, and 50 the operator will at once close the said stop cock and also stop the charging operation, the said stop cock serving primarily as a means of informing the operator when the device has been fully charged. It may also 55 be utilized as a drain, and will be found advantageous also when cleaning or repairing of the mechanism becomes necessary.

While the partitions 25 may be of any desired character consistent with the operation 60 of the invention, I prefer to construct them of corrugated metal plates in order that the finished structure may have the strength necessary to withstand the vibrations caused by the engine and also to prevent being 65 pulled apart under the severe draft or suc-

tion created through the carbureter by the operation of the engine. The perforated corrugated plates possess the maximum strength with the minimum weight. The openings 23 and 24 are arranged at opposite ends of the alternate compartments in order to cause a tortuous circulation of the air currents passing through the device, and in order to further assure this tortuous circulation, the ends of the pans are secured directly to the ends of the housing, as shown at 28, so that the air entering through the inlet 2 will be directed initially upon the surface of the absorbent material in the lowest compartment. The air current will 70 then pass to the opposite end of the housing and will rise to the overflow opening 24 and pass through the same and then over the surface of the material in the compartment containing the said opening, the ascent of the 75 air directly through the housing being prevented by the end of the next superposed compartment, as will be readily understood 80 on reference to Fig. 1.

The carbureter, herein disclosed, is charged 90 with hydrocarbon or other volatile fluid in the described manner, and the throttle valve 13 is adjusted according to the demands from the engine and the conditions under which work is being performed. The engine, having been set in motion, will draw air through the carbureter, and this air will pass over or through the several oil-containing compartments and will vaporize and take up the oil therein so that when the air 100 current passes through the outlet opening 9, it will be laden with a rich gas or hydrocarbon vapor and, consequently, will supply a highly charged gas to the engine. The gas thus supplied, will be further mixed 105 with air at the engine before passing into the combustion chamber of the same, and this final air feed will be controlled by the engineer and regulated according to the 110 exigencies of any particular occasion.

The domes or cup-shaped hoods which are secured over the air inlet and the gas outlet openings provide an enlarged chamber over the said openings in which the air or vapor may collect and, consequently, serve 115 as a cushion to counteract the pulsations of the engine and prevent the said pulsations disturbing the conditions within the carbureter or causing the oil to leak from the several compartments. The ends of the 120 compartments are inclined inward and downward from the ends of the housing so as to provide spaces within which the air may circulate and pass from one level to the next level above the same so as to pass 125 over the surfaces of the absorbent holders within all the compartments, and the particular form of absorbent holder preferably used by me utilizes the force of capillary attraction to bring every drop of the 130

volatile fluid to the surface to be acted upon by the air current.

From the foregoing description, taken in connection with the accompanying drawings, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative, and that such changes may be made when desired as are within the scope of the claims appended hereto.

In my application No. 545,774, for carbureter for household and other uses, filed Feb. 24, 1910, there are shown and described features upon which claims in this case are readable, but no claim is made in said application broadly to such features which is readable upon the disclosure of the present application.

Having thus described the invention, what I claim as new, and desire to secure by Letters Patent, is:—

1. In an apparatus of the class described, a container having the space inclosed by its walls filled with absorbent material to a point short of the free edges of the walls to constitute an unobstructed space between the surface of the absorbent material and the plane of the free edges of the walls of the container, the said container having passages therethrough from the said free space to the exterior of the container.

2. In an apparatus of the class described, a container provided within its confines with a series of spaced parallel partitions with the free edges of the walls of the container and the like edges of the partitions all in substantially one plane, and absorbent material filling the spaces within the container between the partitions and having its exposed surface stopping short of the upper edges of the partitions and walls of the container to provide a series of parallel free spaces coextensive with the length of the partitions.

3. In an apparatus of the class described, a suitable casing, a series of superposed containers therein with a higher container having its bottom of less superficial area than the container thereunder, and a filling of absorbent material for each container stopping short of the top of the container.

4. In an apparatus of the class described, a suitable casing, and a series of containers therein each having sloping sides and ends and each provided with a filling of absorbent material stopping short of the top of the container and having its upper surface substantially coextensive with the cross sectional area of the container coincident with

the surface of the filling material, one end of each container having perforations above the line of the surface of the filling material.

5. In an apparatus of the class described, 70 an inclosing casing, and a series of containers therein having sloping sides and ends and intermediate longitudinal partitions extending from end to end of each container in substantially parallel relation, and a filling of absorbent material coextensive with the space between the walls of each container and the longitudinal partitions therein and stopping short of the top of the container, one end wall of the container being 75 perforated above the surface of the absorbent filling.

6. In an apparatus of the class described, 80 the combination with a housing having an air inlet in one end and a gas outlet at its opposite end, of a series of superposed compartments arranged within the housing in staggered relation and having their ends secured to and inclined inward from the ends of the housing, the alternate compartments being provided with openings in their opposite ends, absorbent holders arranged within the said compartments, and an oil inlet in the top of the housing.

7. In an apparatus of the class described, 85 an inclosing casing, and a series of containers therein having sloping sides and ends and intermediate longitudinal partitions extending from end to end of each container in substantially parallel relation, 100 and a filling of absorbent material coextensive with the space between the walls of each container and the longitudinal partitions therein and stopping short of the top of the container, one end wall of the container being 105 perforated above the surface of the absorbent filling, and the longitudinal partitions being perforated both above and below the surface of the absorbent filling.

8. In an apparatus of the class described, 110 the combination of a series of superposed compartments having air passages between adjacent compartments, longitudinally-disposed partitions within the said compartments provided with transverse openings and vertically corrugated, absorbent holders within the compartments and between said partitions, means for admitting an air current to the space between the compartments, 115 means for supplying oil to the holders within the compartments, and means for carrying off the vapor-laden air.

9. In an apparatus of the class described, 120 a container inclosing a series of spaced parallel partitions, absorbent material filling the space between the partitions and stopping short of the outer edges thereon with matching perforations of the partitions 125 above the surface of the absorbent material, 130

and retaining rods secured to the walls of the container and traversing the matching perforations in the partitions in overlying relation to the absorbent material.

5 10. In an apparatus of the class described, superposed containers each expanding toward the top and each provided with longitudinal partitions having their upper edges flush with the top of the container carrying

10 them, and absorbent material within each container stopping short of the upper edge of the container and filling the container to the height of the upper surface of the mass of absorbent material.

15 11. In an apparatus of the class described, a suitable casing, a series of parallel partitions dividing the lower portion of the interior of the casing into a series of parallel channels, absorbent material filling the 20 spaces between the partitions and stopping short of the upper edges thereof, containers with their bottoms in engaging relation with appropriate ones of the longitudinal partitions, other longitudinal partitions in each container dividing the latter into a series of longitudinal channels, masses of absorbent material filling each channel and each container up to a point short of the upper edges of the container and partitions 25 therein, means for the introduction of liquid hydro-carbon into the casing, means for the introduction of air into the lower portion of the casing, and means for the escape of the air and of the hydro-carbon gases from 30 the top of the casing.

35 12. In an apparatus of the class described, a casing designed to be in substantially horizontal position when in use, a longitudinal series of corrugated and perforated partitions located in the bottom of the casing and in spaced relation one to the other with their upper edges in substantially one plane, a filling of absorbent material coextensive with the spaces between the partitions and 40 stopping short of the upper edges thereof to form a series of parallel channels between the upper surface of the absorbent material and the top edges of the partitions, containers having inclined side and end walls and arranged in superposed staggered relation within the casing above the partitions in the lower part thereof, each container having longitudinally disposed spaced perforated and corrugated partitions 45

50 stopping short of the upper edges thereof to form a series of parallel channels between the upper surface of the absorbent material and the top edges of the partitions, containers having inclined side and end walls and arranged in superposed staggered relation within the casing above the partitions in the lower part thereof, each container having longitudinally disposed spaced perforated and corrugated partitions

55 55 therein dividing the container into longitudinal channels, absorbent material filling the spaces between the partitions in each container and stopping short of the top thereof, each container also having one end 60 wall perforated above the surface of the absorbent material therein, an air inlet for the casing at a point immediately above the absorbent material in the bottom of the casing, an outlet for enriched air at the top of the casing, means for the introduction of a hydrocarbon liquid into the casing at the top thereof, and a valved outlet in the casing communicating therewith at a point above the upper surface of the mass of absorbent material in the bottom of the casing.

65 16. In an apparatus of the class described, a container provided within its confines with a series of spaced parallel partitions with the free edges of the walls of the container and the like edges of the partitions all in substantially one plane, and absorbent material filling the spaces within the container 125 between the partitions and having its exposed surface stopping short of the outer edges of the partitions and walls of the container to provide a series of parallel free spaces coextensive with the length of the 130

tion of a hydro-carbon liquid into the casing at the top thereof.

13. In an apparatus of the class described, the combination with a compartment, of perforated corrugated partitions arranged 70 within the same, and absorbent holders arranged within the said compartment between the said partitions, the latter being extended above the absorbent material.

14. In an apparatus of the class described, 75 the casing, superposed compartments arranged therein and having inclined ends, absorbent holders arranged within the compartments, and perforated partitions located within the compartments and also 80 having inclined ends, some of the perforations in the partitions being covered and some uncovered by the absorbent holders.

15. In an apparatus of the class described, a casing designed to be in substantially 85 horizontal position when in use, a longitudinal series of corrugated and perforated partitions located in the bottom of the casing and in spaced relation one to the other with their upper edges in substantially one 90 plane, a filling of absorbent material coextensive with the spaces between the partitions and stopping short of the upper edges thereof to form a series of parallel channels between the upper surface of the absorbent 95 material and the top edges of the partitions, containers having inclined side and end walls and arranged in superposed staggered relation within the casing above the partitions in the lower part thereof, each container 100 having longitudinally disposed spaced perforated and corrugated partitions therein dividing the container into longitudinal channels, absorbent material filling the spaces between the partitions in 105 each container and stopping short of the top thereof, each container also having one end wall perforated above the surface of the absorbent material therein, an air inlet for the casing at a point immediately above the 110 absorbent material in the bottom of the casing, an outlet for enriched air at the top of the casing, means for the introduction of a hydrocarbon liquid into the casing at the top thereof, and a valved outlet in the casing 115 communicating therewith at a point above the upper surface of the mass of absorbent material in the bottom of the casing.

16. In an apparatus of the class described, a container provided within its confines with a series of spaced parallel partitions with the free edges of the walls of the container and the like edges of the partitions all in substantially one plane, and absorbent material filling the spaces within the container 125 between the partitions and having its exposed surface stopping short of the outer edges of the partitions and walls of the container to provide a series of parallel free spaces coextensive with the length of the 130

partitions, the partitions both where coincident with the filling of absorbent material and beyond the exposed surfaces of the same being perforated, and one wall of the 5 container having passages opening into the channels formed by the spaces between the partitions beyond the surface of the absorbent material.

17. In an apparatus of the class described, a container for a volatile liquid having absorbent material with an exposed surface substantially coextensive with the area of the plane of the container coincident with the surface of the absorbent material, the

said absorbent material having capillary 15 passages terminating at the exposed surface thereof with the ends substantially perpendicular to the direction of travel of air over the exposed surface of the absorbent material.

In testimony that I claim the foregoing as my own, I have hereto affixed my signature in the presence of two witnesses.
